FIG.5

FIG. 1 is a front perspective view from above and to one side of a first embodiment of a quick release hook embodying my design;

FIG. 2 is a perspective view from the other side of the embodiment of FIG. 1;

FIG. 3 is a plan view of the embodiment of FIG. 1;

FIG. 4 is a front perspective view from above and to one side of a second embodiment; and

FIG. 5 is a perspective view from the other side.

I claim:

The ornamental design for a quick release hook, substantially as shown and described.
